SMOKING PIPE

Harry A. Douglas, Bronson, Mich.

Application May 18, 1936, Serial No. 80,227

11 Claims. (Cl. 131—215)

This invention relates generally to smoking devices, and particularly has to do with a pipe.

One object of the invention is to design and construct a pipe having a removable bowl, and an air chamber around the bowl for the purpose of supplying an additional volume of oxygen, so as to more fully insure proper combustion of the tobacco, as well as eliminate undue heating of the pipe in general.

10 Another object of the invention is to provide an offset on the body of the pipe, which is of such a character that the ends thereof will respectively detachably support or carry a pipe stem, and a receptacle for foreign deposits.

15 Another object is to provide a system consisting of one or more passageways that communicate with the air chamber surrounding the bowl and the passageway in the pipe stem, and which may be so arranged that there is practically no 20 opportunity for the smoker to experience what is called "tongue bite"; and this arrangement, including the provision of an auxiliary passageway, arranged in the system of passageways, also serves to entrap any foreign matter, such as 25 tobacco ashes, nicotine, and saliva, whereby to prevent the same from entering the mouth of the smoker through the pipe stem. The passageways and air chamber are preferably so arranged that the receptacle serves as a sump for 30 the nicotine and saliva, while the small particles of tobacco and ashes that happen to drop through the holes in the bottom of the bowl will be retained in the air chamber surrounding the bowl.

35 It is also contemplated to so design and construct the various passageways that the smoke is caused to travel along a tortuous path, in order that the carbonaceous impurities in the smoke will not pass into the mouth of the smoker, 40 and this of course insures a mild, cool refreshing smoke.

A further object of the invention is to arrange a relatively small chamber in the system of passageways, preferably at a point adjacent 45 the lower end of the pipe stem, so that if it is found desirable, a suitable material may be located in the chamber so as to filter the smoke before it enters the mouth of the smoker.

50 A still further object of the invention is to so design and construct the various passageways and chambers, including the various parts comprising the pipe, that all may be easily and quickly cleaned.

55 Other objects and advantages will appear after

considering the following description in connection with the drawing annexed hereto.

Referring to the drawing wherein the details of the preferred principles of design and construction of the smoking pipe are clearly shown, 5 and the various parts are designated by numerals:

Figure 1 shows a vertical section of the preferred embodiment of my invention;

Figure 2 is a vertical section of another embodiment of the invention; and

Figure 3 is a vertical fragmentary section of a third embodiment similar to Figure 2, showing another way whereby to provide an air chamber surrounding the bowl of the pipe.

Referring first and more particularly to the preferred embodiment of the invention shown in Figure 1, numeral 1 generally designates the pipe body which is formed to include a cup 2, which supports a bowl 3, and an integral offset portion 4, which is preferably so constructed that the upper and lower extremities or extensions 5 and 6 thereof will respectively removably support a suitable stem 7, and a receptacle 8 providing a sump for foreign deposits.

The body of the pipe may be made from any suitable material, such as a phenolic condensate, and is preferably formed to provide an air chamber 9 in the cup surrounding the bowl 3. As clearly shown, the upper extremities of the cup 2 and bowl 3, are respectively provided with inwardly and outwardly extending annular portions 10 and 11, which are so constructed that the bowl 3 is adapted to form a friction fit with the cup. The bowl, which is preferably made from a suitable refractory material, may be otherwise detachably attached to the cup 2. Suitable apertures 12 are provided in the bottom of the bowl 3. The air chamber 9 serves to provide an additional volume of oxygen under the burning tobacco so as to support the proper combustion and uniform burning thereof when the pipe is laid aside, and otherwise, said air chamber also serves to insulate the bowl from the cup 2, and this prevents the pipe proper from becoming heated to any great extent.

As to the construction of the pipe stem 7, and the manner in which the same is carried by the extension 5 on the offset 4 of the pipe body, it will be noted that the inner tapered end 13 of the pipe stem is adapted to cooperate with a tapered hole 14, providing a seat therefor; and in order to prevent splitting of the extension, a ferrule 15 is preferably arranged therearound. It is to be understood that the pipe stem may be

made of any suitable material, and may be made straight if so desired, but as here shown, the stem is curved, and has a passageway 16 extending therethrough.

- 5 It is to be noted that the tapered hole 14 in the extension 5 is of a certain depth, and that the inner end 13 of the pipe stem extends inwardly a predetermined distance, in order to 10 preferably provide a relatively small chamber or pocket 17, in which, if so desired, may be placed a suitable fibrous or cellular material 25, impervious to moisture, that will act as an agent to filter the smoke as it is drawn out through the stem by the smoker.
- 15 If found desirable, the filtering material may be impregnated with some suitable chemical so that the smoke will be purified or be given a slightly different pleasing taste. Obviously, any mixture of saliva and nicotine in the passage- 20 way 16 will drain into the pocket 17.

In order to establish communication between the air chamber 9 surrounding the bowl 3, and the passageway 16 in the pipe stem, and the chamber or pocket 17, a passageway 18 is provided in the offset portion 4 of the body of the pipe and, as clearly shown, this passageway extends transversely with respect to the passageway 16 in the pipe stem, and one end of the passageway 18 is so arranged that it opens adjacent the upper extremity of the air chamber 9. Thus far, it will be apparent that the chambers and passageways are so arranged with respect to each other that any fine particles of tobacco or ashes will drop through the apertures 12 in the bottom of the bowl 3 and be retained within the air chamber 9, and that the smoke will be directed along a tortuous path, which will cause any impurities in the smoke, such as nicotine, to adhere to the walls of the chambers and passageways, and as a result, the impurities are removed; and if so desired the smoke may be filtered prior to its being drawn into the mouth of the smoker.

An aperture 19 is preferably provided in the offset portion 4 of the body of the pipe in alignment with the passageway 18 so that after the bowl 3 and the receptacle 8 are removed, the passageway 18 may be properly cleaned.

The lower extremity or extension 6 on the offset portion 4 of the pipe body is preferably tapered to detachably support the tapered tubular receptacle 8, which serves as a sump for foreign deposits such as a mixture of nicotine and saliva. It will be noted that one side of the upper extremity of the receptacle 8 is cut away as indicated at 20, so as not to project across the passageway 18 and interfere with the circulation of the smoke therethrough. The offset portion 4, adjacent the lower extremity thereof is preferably provided with a rebate 21, and a recess 22 that receive the receptacle 8, and these insure that the receptacle 8 will be arranged and seated in a predetermined position. The rebate provides a shoulder which forms an abutment for the continuation portion or long wall of the receptacle. Obviously, the receptacle may be detachably secured to the offset by a snap action connection.

As clearly shown, the lower extremity or shank 70 of the offset portion 4 is spaced from the side wall of the cup and falls short of extending to the bottom wall of said cup. Said extremity is also provided with a passageway 23 extending therethrough, and in line with the passageway 16 in the pipe stem. It is through this passageway

23 that any foreign matter, preferably the nicotine and saliva, but in fact any other foreign matter, drops or drains into the sump receptacle 8. It is to be particularly noted that the passageways 16 and 23 in the pipe stem in the extension 6 are arranged at substantially right-angles to the passageway 18 and aperture 19, and all intersect at the point indicated at 24.

It is thus evident that there is provided a plurality of chambers and passageways, which 10 serve to trap the various impurities in the smoke, and this is of the utmost importance as it is conducive to the health of the smoker. The pipe is sanitary in every respect and odorless to a high degree. It will also be evident that 15 the various parts, including the bowl, stem and the receptacle, are detachably connected to the body of the pipe, and this enables the smoker to easily and quickly clean the chambers and passageways, as well as the parts.

20 Referring to the embodiment of the invention disclosed in Figure 2, it will be apparent that this embodiment is in many respects similar to the construction above described and that there is among other things, two main differences. 25 These differences have to do with the pipe stem, the arrangement of passageways, and one of the chambers.

The body of the pipe, as here shown, is preferably formed or moulded so that the pipe stem 30 30 is integral with the offset portion of the body of the pipe; thus the body is of a one piece construction to which is attached a removable bowl 31, and a sump receptacle 32. An air chamber 33 surrounds the bowl 31.

35 The pipe stem is provided with a passageway 34 that extends continuously therethrough and through the offset 35, the latter of which supports the receptacle 32. The receptacle is here shown as being provided with an aperture 36, and the cup 37 with an aperture 38, which register with each other to form a passageway 39 when the receptacle is properly positioned. It is this passageway 39, and the air chamber in the receptacle 32 that provide means for connecting 40 and establishing communication between the air chamber 33 surrounding the bowl 31, and the passageway 34 in the pipe stem. The passageway 39 is preferably arranged transversely to the passageway 34 in the pipe stem, and the junction point between the passageway 39 and the air chamber 33 is preferably located at a point lower than the junction point between the passageway 18 and the air chamber 9 in the construction illustrated in Figure 1. If found 45 desirable, a pocket 40 may be formed in the offset 35 as to support a suitable filter member 41.

50 Although the receptacle may be frictionally held in place, it is preferably shown in this embodiment as being attached to the offset by means 60 of a snap action connection. This connection may be made by providing a detent 42 in the receptacle which cooperates with a depression 43 in the offset.

55 By reason of this arrangement, it will be evident that the smoke travels from the air chamber 33 through the passageway 39, through the upper part of the receptacle 32, the filter 41, and out through the passageway 34 in the pipe stem, and in this way, any impurities such as fine particles of tobacco, ashes, nicotine and saliva are entrapped in the sump receptacle.

60 Referring to the embodiment shown in Figure 3, it will be evident that the air chamber 50 between the cup 51 and the bowl 52 of the pipe is 75

formed in a different way than shown in Figures 1 and 2, and this is accomplished by providing an annular shoulder portion 53 adjacent the upper and outer extremities of the bowl, in lieu 5 of providing the upper extremities of the cup with an inwardly extending annular portion as shown in the figures mentioned. Although the bowl 52 may be connected to the cup 51 of the pipe in any suitable manner, the connection is 10 here shown as being of the friction type, with the upper extremities of the cup and bowl preferably tapered as indicated at 54.

In both modifications it will be evident that that portion of the cup which is engaged by the 15 receptacle is more or less semi-cylindrical in form to provide an elongated concave seat for the receptacle in order to more fully insure a good foundation for said receptacle.

In view of the foregoing, it will be evident that 20 new principles of design and construction have been embodied in a pipe whereby to accomplish the objects above referred to, and it is to be understood that various immaterial modifications may be made in the construction without in any 25 way departing from the spirit of the invention.

What I claim and desire to secure by Letters Patent is:

1. A pipe comprising a body formed to provide a cup with a portion offset from a side wall 30 thereof, a bowl detachably connected to said cup and a tubular pipe stem arranged on said offset portion, said bowl being spaced from said cup and forming an air chamber adjacent said bowl and communicating with the interior thereof, a 35 receptacle embracingly connected to said offset portion, and said body being formed with a passageway to communicatively connect together the air chamber, receptacle, and the passageway in the pipe stem whereby all the smoke to be drawn 40 through the stem will pass from said bowl to said air chamber and from said chamber directly into and through said receptacle.

2. A pipe comprising a body formed to provide a cup and an offset portion, a bowl detachably connected to said cup and a tubular pipe stem arranged on said offset portion, means forming an air chamber adjacent said bowl and communicating with the interior thereof, a receptacle embracingly connected to said offset portion, and said body being formed with a passageway to communicatively connect together the air chamber, receptacle, and the passageway in the pipe stem whereby all the smoke to be drawn through the stem will pass from said bowl to said 55 air chamber and from said chamber through said receptacle in a path to permit the impurities in the smoke to pass into said receptacle.

3. A pipe comprising a body formed to provide a cup and an offset portion, a bowl connected to said cup and a pipe stem arranged on said offset portion, means forming an air chamber adjacent said bowl and communicating with the interior thereof, a receptacle embracingly connected to said offset portion and having an 60 aperture, and said body being formed with a passageway registering with said aperture to communicatively connect together the air chamber, receptacle, and the passageway in the pipe stem whereby all the smoke to be drawn through 65 the stem will pass from said bowl to said air chamber, and from said chamber in a path to permit the impurities in the smoke to pass into said receptacle.

4. A pipe including the usual body and stem, 70 a bowl supported by said body, an air chamber

surrounding said bowl and communicating with the interior thereof, a secondary chamber, a passageway terminating adjacent the upper extremity of said air chamber and adjacent the lower extremity of said secondary chamber and connected to the opening in the stem whereby to provide a tortuous path of travel for the smoke as it is drawn out through said stem, a tubular extension integral with the body arranged in offset spaced relation to said body and communicating with said passageway, a transverse passageway provided in said extension communicating with said first mentioned passageway, and a receptacle pressed onto said extension and having a continuation designed to cover said 15 transverse passageway.

5. A pipe comprising a body provided with a cup, and an integral angularly arranged offset portion having an upper extremity and a tapered lower extremity with the latter arranged in 20 spaced apart relation to said body to provide a recess, a tubular pipe stem provided adjacent the upper extremity of said offset portion, a bowl and a receptacle respectively detachably connected with respect to said cup and the lower 25 extremity of said offset portion, said receptacle receiving said lower extremity and having a portion frictionally caught within said recess and engaging a side of said cup below said lower extremity for support, said cup provided with an 30 air chamber surrounding said bowl and communicating with the interior thereof, and said offset provided with a plurality of passageways the axes of which intersect each other at a pre-determined location to provide a tortuous path 35 for the smoke whereby the impurities therein may drain and pass through one of said passageways into said receptacle, another of said passageways being arranged at an angle with respect to the longitudinal axis of said cup and intersecting the 40 opening defined by the upper marginal edge of said cup whereby a cleaner may be inserted through either end of said passageway.

6. A pipe including an outer bowl formed with a lateral shank having its lower end spaced 45 from the outer bowl to form a recess, a mouthpiece connected to the shank, a bore in the extension in alignment with the bore in the mouthpiece, an inner bowl positioned within the outer bowl and having a portion thereof in spaced relation to the wall of the outer bowl forming a 50 passage, a second passage extending transverse to the extension bore and in communication with the first passage, and the bores of the mouthpiece and extension being adapted to communicate 55 with the atmosphere surrounding the extension, and a receptacle having a short wall adapted to be received in said recess and a long wall adapted to embrace the shank extension and close one end of the transverse passage, said receptacle in 60 its assembled position on said extension constituting a closure for one end of the transverse passage and a liquid receptacle enclosure for the shank bore and when removed permitting the transverse passage, and shank bore and mouthpiece bore to be cleaned through the shank end thereof.

7. A pipe including an outer bowl formed with a longitudinal concave seat, and a lateral shank having its lower end spaced from the outer bowl 70 to form a recess, a mouthpiece connected to the shank, a bore in the extension in alignment with the bore in the mouthpiece, an inner bowl positioned within the outer bowl and having a portion thereof in spaced relation to the wall of the 75

- outer bowl forming a passage, a second passage extending transverse to the extension bore and in communication with the first passage, and the bores of the mouthpiece and extension being adapted to communicate with the atmosphere surrounding the extension, and a receptacle having a short wall adapted to be received in said recess and a long wall adapted to embrace the shank extension and close one end of the transverse passage, said receptacle in its assembled position on said extension resting on said seat and constituting a liquid receptacle enclosure for the shank bore and when removed permitting the transverse passage, and shank bore and mouthpiece bore to be cleaned through the shank end thereof.
8. A pipe comprising a body formed to provide a cup, and an integral enlargement having tubular upper and lower extremities arranged in offset relation to and along one side wall of said cup and in communication with the interior of said cup, a tubular stem provided adjacent said upper extremity, said lower extremity being arranged in spaced apart relation to said cup to provide a recess, and a receptacle cooperating with said lower extremity and having portions, one of which engages said side wall of said cup below said enlargement for support, and the other portion being caught within said recess.
9. A pipe having a bowl and a stem, said bowl having a wall formed with a seat adjacent the stem, and said stem having a shank adjacent and spaced from said wall and short from the end of said wall, said stem having a shoulder, and a receptacle having one wall adapted to be

received in the space between the shank and wall of the bowl and resting on said seat, and a second wall of greater length partially surrounding said shank and engaging said shoulder.

10. A pipe having a bowl and a stem, said bowl having a wall adjacent the stem, and said stem having a shank adjacent and spaced from said wall and short from the end of said wall, said stem having a shoulder, and a receptacle having one wall adapted to be received in the space between the shank and wall of the bowl and in abutting relation to said wall of the bowl, and a second wall of greater length partially surrounding said extension and engaging said shoulder.

11. A pipe including an outer bowl and a shank formed of the same material and in one piece, said shank being offset with respect to one wall of the bowl and having one end thereof spaced from and extending only along a part of said wall to form a recess, said shank having a longitudinal bore therethrough terminating in the end of the shank spaced from the wall, said shank having a shoulder on its outer side of curved formation, a bowl supported on the outer bowl in spaced relation thereto forming a passage, openings in the second bowl and in the wall of the outer bowl, and a receptacle having one short wall and one long wall, said short wall fitting in the recess between the shank and the outer bowl wall and said long wall abutting the shoulder of said shank, said receptacle constituting a container for moisture.

HARRY A. DOUGLAS. 35
